United States Patent Office

Des. 193,267
Patented July 24, 1962

193,267

DICTATING MACHINE

Peter Sieber, Frankfurt-Main-Seckbach, and Arnold Schurer, Offenbach-Main, Germany, assignors to Olympia Werke A.G., Wilhelmshaven, Germany

Filed Nov. 4, 1960, Ser. No. 62,897

Term of patent 14 years

(Cl. D26—14)

Fig. 1.

Fig. 2.

FIG. 1 is a perspective view as seen from the front, top and side of a dictating machine, showing our new design, the opposite side being substantially a mirror image thereof; and

FIG. 2 is a front elevational view thereof.

The essential features of the design reside in the portions shown in full lines on the drawing.

We claim:

The ornamental design for a dictating machine, as shown and described.
